UNITED STATES PATENT OFFICE.

ALBERT D. GARRETSON AND HARRY D. GARRETSON, OF BUFFALO, NEW YORK.

AIR-NAVIGATING CRAFT.

1,179,298.

Specification of Letters Patent.

Patented Apr. 11, 1916.

Application filed June 17, 1910. Serial No. 567,358.

To all whom it may concern:

Be it known that we, ALBERT D. GARRETSON and HARRY D. GARRETSON, both citizens of the United States, residing at Buffalo, 5 county of Erie, State of New York, have invented a certain new and useful Improvement 10 in Air-Navigating Craft, and declare the following to be a full, clear, and exact description of the same, such as will enable others skilled in the art to which it pertains to make and use the same, reference being had to the accompanying drawings, which form a part of this specification.

This invention relates to air navigation.

15 It has for its object an improved air navigating craft of the Helicopter type in which the blades of the propeller are attached to long, flexible, restraining or holding cables, which allow the blades to hang from their 20 points of support in a vertical condition when the propelling mechanism is not in action, but which, because of centrifugal force, restrain or hold the blades with their long axes in an approximately horizontal condition 25 or position when the motive power has attained its full force; the blades with their supports begin to change from their vertical condition to their horizontal condition immediately after the prime motor begins its 30 action and the centrifugal force begins to act upon them.

In the drawings:—Figure 1, is an elevation 35 of the craft in a position of rest. Fig. 2, is an elevation of the craft with the propeller in operative position. Fig. 3, is a horizontal projection of the craft with the propeller in operative position. Fig. 4, is a detail of the wing blade and its connections. Fig. 5, is a diagram showing the relation of 40 the components of force acting on a wing blade. Fig. 6, is a diagram showing a wing blade with a single attachment for the restraining cable and with balancing attachment upon the blade. Fig. 7, is a diagram 45 of the components of force on the blade shown in Fig. 6. Fig. 8, is a diagram of the forces tending to keep the craft in an upright position. Fig. 9, is a detail of a means of applying motive power to the wing arm. 50 Fig. 10 is a plan view of the mast and the balancing planes.

The craft consists of a cage or carriage 1, to be occupied by the traveler; this cage hangs from a post 3 to which it is swiveled, 55 the post may be considered as the main

foundation member of the entire structure; it carries a motor M that drives two sets of arms 8 and 9. The cage 1 hangs below it, and a mast supporting a balancing plane rises above it; the two sets of arms move in 60 opposite directions. The motor is secured to the post on a table T which supports also the fuel tank F. The carriage for the passenger is swiveled to the post and is provided with means which prevent its ready 65 turning thereon or therewith.

The carriage consists of a rectangular frame work 1 suspended by a frame or cage 2 from the post 3; the upper end of the post 3 supports a table T on which is mounted 70 the main driving motor M. Below the table on the post 3 is a sleeve 4 to which is secured a ring 5 that carries the lower set of arms 8, and sleeved on the hub of the ring 5 is a ring 6 which carries the upper set of arms 9. 75 A spur gear 7 extending from the hub or sleeve 4 engages a spur gear or pinion 8^g that is driven by the motor; the same pinion 8^g engages an annular gear 6^a secured to the ring 6. The pinion 8^g is on a shaft 8^a 80 journaled in bearings on the table T and driven by means of miter gear 8^b by a miter gear 8^c on the crank shaft of the engine M. The opposite end of the crank shaft is provided with a miter pinion 8^d, which meshes 85 with the miter gear 8^e on the long shaft 8^e that extends down through the hollow interior of the post 3, and is utilized for engine starting purposes. The sleeve 4 rests on collar 3^a on the post 3 above the swivel joint 2. The fuel tank F rests on the table T, and is 90 connected with the engine in any suitable way, and feeds its fuel to the engine through a throttle-governed valve V controlled by manually actuated reach rod S. The mast R rises from the table T and supports at its upper end balancing planes 10, that will be 95 spoken of more at length hereinafter.

The specific means by which the opposite 100 motions are given to these two sets of arms does not form any part of this invention; any other means might be employed for producing the opposite rotation of the arms 8 and 9, without departing from the invention 105 herein contained. The relative speed of the two wing-supporting members is provided for by the proper determination of the sizes and orbits of the wing blades 14 and 17, and properly proportioning the gear with respect thereto; it is desirable to give to the 110

two sets of arms such speed as will produce a substantially equal resistance and a consequent substantially equal lifting power, all of which is a matter of computation. The lower diverging arms 8, carried by the ring 5, have cables 13 attached thereto, and from the outer or free ends of these cables hang the wing blades 14; to the upper diverging arms 9 are attached cables 19 from the ends 10 of which hang the wing blades 17 of the upper set. The attachment of the blade to the cable may be double as indicated in Fig. 4, or single as indicated in Fig. 6. With the double attachment indicated in Fig. 4, 15 there is an automatic adjustment of the wing blade, which automatic adjustment is controlled by the speed of rotation of the wing. This automatic adjustment is effected by the air resistance to the wing blade, which 20 tends to twist the blade on its axis against the holding tension of the cable, whereas the cable tends to twist the wing blade in the opposite direction; the diagram Fig. 5 shows this. With the single connection of 25 Fig. 6, we use an attachment 17^b hinged to the wing blade 17^a, which produces the same automatic governing result (see diagram Fig. 7). The lifting force of the wing blade is converted into a progressive force to produce a traveling movement of the craft by 30 shifting the center of gravity of the entire craft, which is done by the occupant changing his position. The car or carriage part of the vessel is provided with a tail 18, 35 which tends to prevent the cage or car from revolving with the post; this tail is made large enough to furnish a resistance plane which overcomes the tendency of the car to rotate with the post 3, which sometimes 40 rotates with one or the other of the wing arm frames.

Change in direction of the progressive motion of the craft is effected by manipulating the reach rod 20 of a clutch 21 on the 45 cage, which causes the engagement of one lever or the other of the clutch with either the collar 3^a or the sleeve 4; as these parts are caused to rotate in opposite directions, the change in direction of the craft's movement is effected accordingly.

The stability of the normally upright position of the car is assured by series of balancing planes 10, as shown in Fig. 10. These are acted upon by the air against which the 55 craft is advancing and they co-act with the weight of the craft itself to keep the car in a substantially upright position, with the post 3 inclining forward, and with its top advanced to produce the traveling movement of the car. The tail 18 is arranged to 60 fold so that it may be folded away from the path of the wings when the wings drop to or toward the position of rest shown in Fig. 1.

65 A friction clutch or brake 21 is arranged

to engage against the collar 3^a and the surface of the sleeve 4; this is actuated manually by means of reach rod 20 which in turn actuates one or the other part of the pivoted brake members 21.

What we claim is:—

1. An air navigating craft, comprising a central post, a table carried by said post, a motor carried by said table, a sleeve surrounding said post and adapted to be rotated by said motor, a plurality of arms rotatable with said sleeve, flexibly mounted members normally pendent from said arms and adapted to be swung toward a horizontal position by the rotation of said sleeve.

2. An air navigating craft, comprising a central post, a table carried on the top of said post supporting the craft propelling means, a mast carried by said table and a series of balancing planes carried by said mast.

3. An air navigating craft, comprising a post, a table carried by said post, a motor carried by said table, a sleeve rotatably mounted around said post, means connecting said motor with said sleeve for rotating the same, an upper ring member rotatably mounted on said sleeve, a lower ring member rigidly mounted on said sleeve, a plurality of arms carried by each of said rings and propelling means flexibly connected with each series of said arms.

4. An air navigating craft, comprising a rigid post, a table carried by said post, a motor carried by said table, a sleeve rotatably mounted around said post, means connecting said motor and said sleeve for rotating said sleeve, an upper ring rotatably mounted around said sleeve and a lower ring rigidly mounted on said sleeve, means for rotating said rings in opposite directions, a series of arms secured to each of said rings and a series of vanes secured to each of said arms by flexible means.

5. An air navigating craft, comprising a central post, a table carried by said post, a motor carried by said table, a sleeve rotatably surrounding said post, means connecting said motor with said sleeve for rotating said sleeve, a collar rigidly secured to said post below said sleeve, a carriage pivotally supported on said post, a clutch carried by said carriage and means operable in said carriage for throwing said clutch into engagement with said collar or into engagement with said sleeve.

6. In an air navigating craft, the combination with a post, a table carried by said post, a motor carried by said table, a vertical shaft carried by said table and adapted to be actuated by said motor, a plurality of sets of wing carrying arms rotatably arranged, means carried by said table for causing the rotation of the sets of arms in

opposite directions and wing vanes flexibly connected to said wing arms and adapted to swing outwardly therefrom when said arms are in motion, and pendent therefrom when 5 said arms are not in motion.

7. In an air navigating craft, the combination with a post, a table carried by said post, a motor carried by said table, a mast carried by said table, a series of balancing 10 vanes carried at the level of the top of said mast in angular relation to each other, a vertical shaft rotatably carried by said table and adapted to be actuated by said motor, a plurality of sets of wing carrying arms rotatably arranged, means carried by said 15 table for causing the rotation of the sets of arms in opposite directions and wing vanes flexibly connected to said arms and adapted to swing outwardly therefrom when said 20 arms are in motion, and pendent therefrom when said arms are not in motion.

8. In an air navigating craft a carriage, a motor, an upwardly extending mast above 25 said carriage, a plurality of wing members flexibly mounted in position to be horizontally rotated by said motor, means for driving said wing members in opposite directions, a balancing vane at the upper end of said mast and at right angles thereto, said 30 wings being intermediate of said balancing vane and said carriage.

9. In an air navigating craft, in combination with a motor and a shaft therefor, a carriage supported beneath said motor, an 35 upwardly extending mast projecting above said motor, a balancing vane at the upper end of said mast, wing members rotatably mounted upon suitable supports and arranged to be rotated by said shaft, said wing

members being flexibly connected to said 40 shaft.

10. In the propeller of a helicopter, the combination of a plurality of series of rotative arms adapted to move in opposite directions, the one to the other, a cable attached at its center portion to each of said arms and a series of wing vanes, each of said vanes being secured to the ends of two of said cables, whereby the lifting action 45 of each is automatically varied by changes in its angular position with respect to the rotation caused by its arm, each vane being pendent from its supporting arm when the same is at rest.

11. In an air navigating craft, the combination with a carriage, a frame secured to said carriage, a motor supported above said carriage, a shaft rotatably actuated by said motor, a plurality of series of supporting arms rotatably arranged about said shaft as 55 a center, intermediate mechanisms, whereby the members of each of said series may be actuated in opposite directions by the rotation of said shaft, a cable attached at its center portion to each of said arms, and a series of wing vanes, each of said vanes being secured to the ends of two of said cables, and a clutch mechanism carried by said 60 frame for directing the travel of said carriage.

In testimony whereof we sign this specification in the presence of two witnesses.
